ATTORNEY

UNITED STATES PATENT OFFICE.

HOMER H. ELLIOTT, OF ROSE, KANSAS.

LAMP.

1,301,921.

Specification of Letters Patent. Patented Apr. 29, 1919.

Application filed April 19, 1918. Serial No. 229,605.

To all whom it may concern:

Be it known that I, HOMER H. ELLIOTT, a citizen of the United States, residing at Rose, in the county of Woodson and State of 5 Kansas, have invented certain new and useful Improvements in Lamps, of which the following is a specification.

This invention is a lamp attachment and has for its principal object the production 10 of a simple and efficient means for determining the quantity of oil within the lamp.

Another object of this invention is the production of a lamp attachment which consists of a transparent tube connected to the 15 bowl of the lamp, thus permitting the oil level within the bowl of the lamp to be easily determined.

Another object of this invention is the production of a lamp attachment which consists of a transparent tube having inwardly 20 extending ends, the ends being carried by necks extending from the bowl of the lamp, thus holding the tube against displacement and permitting the oil level within the bowl 25 to be determined.

Another object of this invention is the production of a lamp attachment wherein the tube is curved to conform to the contour of the bowl of the lamp, thus being in a substantially 30 out-of-the-way position and also disclosing a neat appearance, as well as disclosing the quantity of oil within the bowl.

Broadly stated, this invention consists of a transparent tube curved throughout practically 35 its entire length to conform to the contour of the bowl of the lamp, the ends of the tube extending inwardly, a lamp bowl having outwardly extending hollow necks, said necks engaging the inwardly extending 40 ends of the tube, thus holding the tube against displacement and permitting the oil level to be easily determined.

With these and other objects in view, this invention consists of certain novel combinations, construction, and arrangement of parts as will be hereinafter fully described and claimed.

One practical form of construction and assembly of the present invention will be 50 hereinafter described and is illustrated in the accompanying drawing, in which—

Figure 1 is a side elevation of the attachment as applied to the bowl of a lamp, portions of the bowl being broken away, and

55 Fig. 2 is a sectional view taken on the line 2—2 of Fig. 1.

In the preferred embodiment of the present invention about to be described, it will be noted that the attachment is used in connection with a bowl 5 of a lamp, said bowl 60 being carried by a pedestal 6 and having a burner 7. The present invention is especially adapted for use in connection with non-transparent bowls, such as where the bowls are formed of metal or of a non-transparent 65 glass, thus preventing ready determination of the amount of oil within the bowl. Consequently, without using the present invention, such lamps are frequently filled until they overflow and under other 70 conditions they are burnt dry, as it is comparatively difficult to determine the quantity of oil within the bowl. The gage tube 8 is formed of transparent glass and is elongated, as illustrated clearly in Fig. 1. This 75 tube 8 is curved throughout its entire length, thus permitting the same to be carried at a point adjacent the outer surface of the bowl 5. The ends 9 of the tube 8 extend inwardly, although easy access may be had 80 to the interior of this tube 8. The lamp bowl 5 is provided with openings 10 in its top and bottom portions, while necks 11 are formed on the bowl 5 and extend outwardly and surround the openings 10.

85 The inwardly extending ends 9 of the tube 8 project into the openings 10 of the bowl 5, thus communicating with the interior of the bowl. The necks 11 of the bowl bear upon the inwardly extending ends 9 and in 90 this way form a liquid tight joint at each end of the tube 8. Since the ends 9 of this tube communicate with the top and bottom portions of the bowl 5, it is obvious an accurate estimation of the amount of oil within the bowl 5 may be readily determined, since the bowl will be entirely empty of oil when the oil reaches the bottom tube 8, or the bowl will be entirely filled, almost to a point of overflowing when the oil reaches 95 the top of the tube 8.

When the gage tube 8 is being blown and is still hot, the ends thereof are bent into engagement with the necks 11. Before the burner 7 is placed in engagement with the 105 bowl 5, a suitable implement may be inserted into the bowl to engage the bent ends and swing the same for causing the bent ends and necks to form a tight closure. Therefore the tube will be firmly held in engagement with the bowl.

110 Since the ends 9 extend inwardly, it is

obvious that after the device has been assembled, the tube will be positively held against displacement, without secondary securing means, as the inwardly extending 5 ends will prevent such action. Also, since the tube conforms in contour to the bowl 5, it will be in an out-of-the-way position and will not present an ill appearance. In fact, if so desired, the bowl could be provided 10 with a groove within which the tube could be fitted, thus presenting an even outer surface around the bowl and also constitute a shield for protecting the tube.

From the foregoing description, it is obvious 15 a very simple and efficient attachment has been provided for lamp bowls of the ordinary nature, which consist of the transparent tube having inwardly extending ends, communicating with the top and bottom 20 of the bowl, thus disclosing the amount of oil within the bowl, while the engagement of the tube with the bowl is such as will prevent accidental displacement of the tube.

The foregoing description and the drawings 25 have reference to what may be considered the preferred, or approved, form of my invention. It is to be understood that I may make such changes in construction and arrangement and combination of parts, materials, dimensions, et cetera, as may prove 30 expedient and fall within the scope of the appended claims.

Having thus fully described my invention, what I claim as new and desire to secure by Letters Patent, is:—

1. In a device of the class described, the combination of a bowl having openings formed in its top and bottom, said bowl having necks extending therefrom and sur-

rounding said openings, a gage tube curved 40 throughout its entire length to conform to the contour of said bowl, said tube having inwardly extending ends, said ends being carried by said necks and communicating with the interior of said bowl, thus accurately disclosing the oil level within said bowl, said inwardly extending ends and said necks holding said tube against accidental displacement independent of secondary securing means. 45

2. In a device of the class described, the combination of a bowl having openings formed in its top and bottom, said bowl having necks extending therefrom and surrounding said openings, a gage tube conforming in shape to the contour of said bowl having angularly extending ends carried by said necks and communicating with the interior of said bowl, and said ends and necks holding said tube against accidental displacement. 50

3. In a device of the class described, the combination of a bowl having openings formed in its top and bottom, a gage tube having ends extending at an acute angle 65 thereto, said ends inserted in said openings and communicating with the interior of said bowl, whereby the oil level within the bowl may be disclosed, while the inter-engagement between said ends will hold said tube 70 against displacement.

In testimony whereof I affix my signature in presence of two witnesses.

HOMER H. ELLIOTT.
